UNITED STATES PATENT OFFICE.

RAYMOND D. JOHNSON, OF NIAGARA FALLS, NEW YORK.

MEANS FOR REGULATING WATER-PRESSES IN LONG UNDERGROUND TAIL-RACES.

1,087,169.

Specification of Letters Patent.

Patented Feb. 17, 1914.

Application filed January 6, 1913. Serial No. 740,568.

To all whom it may concern:

Be it known that I, RAYMOND D. JOHNSON, a citizen of the United States, residing at Niagara Falls, in the county of Niagara and State of New York, have invented certain new and useful Improvements in Means for Regulating Water-Pressures in Long Underground Tail-Races, of which the following is a specification.

This invention relates to apparatus for assisting the speed-regulation of turbines in water-power installations having long underground tail-races, running full of water escaping at high velocities.

The invention consists in means for counteracting the abrupt and severe pressure-changes ordinarily occasioned by the inertia of the long column of water in such a filled tail-race, when the wheel-gates are suddenly opened or closed.

When the water escaping from a turbine is carried away by a long underground tail-race, running full with air excluded, and with the water therein under pressure, difficulty arises when the turbine-gates are shifted to compensate for changes of load. The sudden requisition made upon the tail-race to deliver more or less water, which can only be satisfied by a rapid acceleration or retardation of the velocity of the long column of water therein, causes an abrupt and severe change of water-pressure, which not only renders wheel-speed regulation extremely difficult or impossible, but may result in damage to the plant. For example, if the gates are suddenly closed, the inertia of the column of effluent water may momentarily draw a vacuum underneath the turbine, after which the column of water will surge backward to fill the vacuum, producing a dangerous water-hammer in the draft-chamber of the turbine. Conversely, when the gates are suddenly opened, the effort to instantly force more water through the tail-

race will produce a high back-pressure, tending to counteract the effect of the increased gate-opening, and the turbine will slow down, thus making satisfactory operation impossible for most commercial purposes.

This retardation of wheel-speed will be quickly followed by a rapid and dangerous rise of speed, due to the subsequent reduction of pressure caused by the outward pendulum-like swing of the long water-column.

On account of these difficulties in operating a plant having a long underground tail-

race when the race is run full, it is the usual practice to make the race or tunnel of a cross-section much greater than that necessary for the economical discharge of the water, and to carry its mouth into the river above the high-water-mark, thereby allowing air to enter the mouth and causing a space filled with air to exist above the stream of water at all points in the tunnel, back to the turbine draft-tube. While satisfactory wheel-regulation is thus obtained, it is at a great sacrifice of water-head and with a large initial expense for excavation.

The present invention is a hydraulic regulator connected to the turbine draft-tube, or to the tail-race in proximity to the turbine, which mitigates the abrupt changes of water-pressure in the race due to the sudden shifting of the wheel-gates, thereby enabling a race of minimum gradient and cross-section to be run full of water at high velocities.

The preferred apparatus is shown in the accompanying drawing, in which the figure 80 is a transverse vertical section of a water-power plant, the plane of section passing through the wheel-pit, regulator-pit, tail-race and regulator supply-passage, the turbine being shown in elevation and the regulator in axial section.

This installation comprises a vertical wheel-shaft 1, on the base of which is seated a turbine 2, fed by a penstock 3. The water from the turbine escapes through a vertical draft-tube 4, shown as a passage through the concrete base, into a tail-race 5. The mouth 6 of this race opens into the river-bed 7 at the low-water-level. At one side of and opening into the wheel-shaft is the regulator-pit 8.

The hydraulic regulator comprises a vertical tank 9, preferably a cylindrical tank open at the top. In the bottom of this tank is a central opening 10, which communicates with the lower end of the draft-tube 4 through a curved passage 11 in the concrete base. Such a simple storage-tank, connected to the draft-tube, acts as a regulator. When a steady load prevails, and the water is running through the race at constant velocity, the surface 12 of the water in the tank will be at a level above the level 13 of water in the river by an amount corresponding to the head required to overcome the water-losses due to friction and impact, the dotted line 14 joining the two levels 12, 13 being the

hydraulic gradient. If now a sudden change of load is demanded, the immediate water requirement of the race, either plus or minus, will be furnished by the tank, acting as a storage reservoir, and the necessary acceleration or retardation of the long column of water in the race will be gently effected by the gradual increase or decrease of pressure within the tank, as the level rises or falls therein. Otherwise stated, the excess or deficiency of water temporarily not cared for by the tail-race will be stored in or supplied by the tank. While such a simple storage-tank is operative as a regulator, it is subject to the disadvantage that the long column of water in the race acts as a pendulum, in which, when once set into vibration by a change of load, the velocity changes tend to oscillate back and forth, even if there is no further change in the position of the wheel-gates. And if the gates are shifted by their speed-regulator in synchronism with this pendulum-like swing, the amplitude of oscillation is thereby greatly increased and undue pressure-changes will result. To overcome this oscillation of the column of water in the race, it is preferred to interpose between the regulator-tank and the tail-race a resistance or restricted passage for the water. And in order to mitigate the sudden changes of pressure which would otherwise be caused by this restriction, a stand-pipe is provided, which itself has some water-capacity and in which the water changes its level somewhat gradually, rising or falling therein to a point where the pressure due to the difference in the levels in the tank and the stand-pipe is sufficient to force through the restricted opening the excess or deficiency of water to be temporarily cared for. In the apparatus illustrated, this stand-pipe comprises a pipe 15, extending downward through and in proximity to a short neck or flange 16, constituting a continuation of the central tank-opening 10. The annular passage 17 between the pipe 15 and the neck 16 is proportioned to give a predetermined resistance to the flow of water therethrough. This stand-pipe, by reason of the enforced separation of the pressure-level therein and the level of water outside in the storage-tank, acts like a dash-pot, to damp the oscillation of the water through the passage 11, between the tail-race and regulator, greatly reducing the amplitude of the vibration; in fact, with proper design, its action may be dead-beat, entirely doing away with the pendulum-like swing of the column of water in the race, a load-change producing but one swing or change of level in the tank, corresponding simply to the unavoidable change in hydraulic gradient following the load-change. The mathematical theory of the "differential action" of this stand-pipe has been fully described by me in an article, No. 1204, en-

titled "The surge tank in water power plants," published by the American Society of Mechanical Engineers. The principle is similar to that utilized in my apparatus for cushioning hydraulic pressures in turbine penstocks, covered by my U. S. Letters Patent No. 962,355, granted June 21, 1910.

While the stand-pipe 15 preferably extends above the tank 9, to permit a very considerable rise of the pressure-level therein, the use of a single imperforate pipe is disadvantageous, on account of the large volumes of water which might be projected from the top of such pipe when the demand for power is suddenly increased, falling back into the tank from a considerable height with a heavy hammering action. It is therefore preferred to provide outlet passages between the lower and upper ends of this pipe, and not far above the normal level of water in the tank. While a single pipe having openings through its wall may be employed, it is preferred to use a double stand-pipe, the upper section 15' of which is of smaller diameter than the lower section, the lower end of the upper section being fixed concentrically in the upper end of the main pipe to leave an annular passage 18, through which the bulk of the water rising in the pipe 15 may escape into the tank. It will be noted that the annular passages 17, 18 are in line with the normal flow of water, and set up no eddy-currents to interfere with the normal damping action.

I claim:

1. In combination with a water-power plant comprising a water-wheel and a long closed tail-race, a regulator consisting of a storage-tank connected to the tail-race in proximity to the water-wheel.

2. In combination with a water-power plant comprising a water-wheel and a long closed tail-race, a storage tank, a passage connecting said tank and race, in proximity to the water-wheel, and means for restricting the flow of water through said passage.

3. In combination with a water-power plant comprising a water-wheel and a long closed tail-race, a storage tank, a passage connecting said tank and race, in proximity to the water-wheel, means for restricting the flow of water through said passage, and means for modifying the water-pressure in said race in accordance with but at a more rapid rate than the change of pressure indicated by the change of water-level in said tank.

4. In combination with a water-power plant comprising a water-wheel and a long closed tail-race, a storage tank, a passage connecting said tank and race, in proximity to the water-wheel, means for restricting the flow of water through said passage, and a stand-pipe connected with said passage,

- 5 serving to modify the water-pressure in said race in accordance with but at a more rapid rate than the change of pressure indicated by the change of water-level in said tank.
- 5 6. In combination with a water-power plant comprising a water-wheel and a long closed tail-race, a storage tank having a bottom opening, connected to said race, and a stand-pipe within said tank and extending into its bottom opening, leaving a restricted passage.
- 10 6. In combination with a water-power plant comprising a water-wheel and a long closed tail-race, a storage tank, a passage connecting said tank and race, in proximity to the water-wheel, means for restricting the flow of water through said passage, and a stand-pipe connected with said passage, serving to modify the water-pressure in said race in accordance with but at a more rapid rate than the change of pressure indicated by the change of water-level in said tank, said stand-pipe having an overflow outlet between its ends.
- 15 7. In combination with a water-power plant comprising a water-wheel and a long closed tail-race, a storage tank having a bottom opening, a conduit connecting said tank-opening and race, and a stand-pipe within said tank and extending into its bottom opening, leaving a restricted passage, said stand-pipe having an overflow outlet between its ends.
- 20 8. In combination with a water-power plant comprising a water-wheel and a long closed tail-race, a storage tank having a bottom opening, a conduit connecting said tank-opening and race, and a stand-pipe
- 25 within said tank and extending into its bottom opening, leaving a restricted passage, 46 said stand-pipe comprising two concentric sections with an intermediate overflow passage.
9. In combination with a closed water-conduit, a differential hydraulic regulator 47 consisting of a tank directly connected to said conduit by a restricted passage, and a stand-pipe also directly connected to said conduit.
10. In combination with a closed water-conduit, a differential hydraulic regulator 50 consisting of a tank directly connected to said conduit by a restricted passage, and a stand-pipe also directly connected to said conduit, said stand-pipe having an opening 55 between its ends in position to discharge water into said tank.
11. In combination with a closed water-conduit, a differential hydraulic regulator consisting of a tank having an opening connected to said conduit, and a stand-pipe extending into said opening.
12. In combination with a closed water-conduit, a differential hydraulic regulator 65 consisting of a tank having an opening connected to said conduit, and a stand-pipe extending into said opening, having a restricted passage, said stand-pipe comprising two concentric sections with an intermediate overflow passage.
- 70 In testimony whereof I affix my signature in presence of two witnesses.
